(57) **CLAIM**

The ornamental design for a self adjusting furniture glide, as shown and described.

DESCRIPTION

FIG. 1 is a isometric view of a furniture glide in accordance with the present invention;

FIG. 2 is a side elevational view of the furniture glide of FIG. 1;

FIG. 3 is a top plan view of the furniture glide of FIG. 1; and, FIG. 4 is a bottom plan view of the furniture glide of FIG. 1. The broken lines immediately adjacent the shaded areas represent the bounds of the claim and all other broken lines are for illustrative purposes only. None of the broken lines form part of the claimed design.
